UNITED STATES PATENT OFFICE.

AXEL W. HALLENBORG, OF NEWARK, NEW JERSEY.

OIL-GAS PRODUCER AND BURNER.

Application filed July 5, 1927. Serial No. 203,324.

This invention relates to converting oil into gas for use as a fuel and also for storage and for other purposes. By way of example it is illustrated in the form of heating means 5 for a steam-boiler, for house heating. One of the objects is to economize oil, and another object is to produce a simple, durable, inexpensive, compact and reliable apparatus, and to eliminate the numerous moving parts commonly used in house-heating oil-burners.

Many burners spray the fuel-oil into a jet of air, which makes a yellow flame and is uneconomical. But by this invention a mixture of hydrocarbon gas and air is secured, which produces a blue flame which furnishes great heat and is economical.

In small burners for use with pot-stoves and other small heaters, a saucer of burning alcohol is ignited to heat a bulb containing oil which is converted into gas by the heat, the gas being led to a burner or jet which is ignited under said bulb, whereby there is effected more conversion of oil into gas; such devices being usually provided with baffles and devices, upon which to collect the lampblack which is freely formed and deposited in such heaters and of course tends to find its way to the burner-jet and clog the same, thereby rendering the heater inefficient and impracticable. The oil inevitably forms carbon during such distillation, which deposits in many places, and renders the device undependable, especially when it chokes up the burner-jets, the only way for preventing this being to provide for the collection of the solid carbon from the gas before the gas reaches the jet. Hence such devices have to be made convenient for disassembling of the same for access to the interior, to permit removal of the lampblack at short intervals.

The present invention involves a different principle, in that provision is made for avoiding deposit of lampblack, and the choking of the burner thereby. In place of the old practice of collecting the cooled carbon-deposit by means of baffles in corners in the retort or bulb, the retort is made without corners and with a very smooth bore of small diameter and very long, making a tube or tubular passage through which the gas is caused to travel at as high a speed as practicable. By this means, the deposit of lampblack in the retort is avoided. There may occur some condensation of carbon, but such

solid carbon exists in the form of very fine particles, which are borne along by the current of gas speeding through the tubular raceway which forms the retort. The carbon-condensations, these very small bodies, are swept up by the current, and are prevented from collecting or combining to form clots or accumulations of lampblack, whereby choking of the passages and of the needle-valve is prevented. No places are left into which the lampblack can lodge or drift, and the gas is kept moving so fast as to give little or no opportunity for forming a drift.

Many of the oil-burners in common use do not mix air and fuel until after the place of ignition is reached. In many instances, a mixture of air and oil spray is made simultaneous with the ignition and combustion. A novel feature of the present invention is that it employs for heavy oil-burners a principle which has heretofore been confined to burning illuminating gas or natural gas in ordinary gas-stoves, etc., that is, the well-known Bunsen principle of mixing air and gas intimately before ignition. The oil is first converted into gas, and then fed through a needle-valve or the like to a Bunsen burner.

One of the features of the invention is in the use of a fire-box in burning oil-gas, and in providing for the mixing chamber of the Bunsen burner to be contained within the improved fire-box, where the mixing oil-gas and air are pre-heated on their way to the delivery end of the Bunsen burner.

Other features and advantages will hereinafter appear.

In the accompanying drawings:

Figure 1 is a sectional central elevation, 95 showing details of a house-heating furnace having the present improvements applied thereto.

Figure 2 is a perspective view of the furnace and the oil-burning apparatus.

Figure 3 is a perspective view of portions of the oil-burning apparatus which are within the boiler.

Fuel-oil 10 in tank 11 is under ten or twenty pounds pressure of overlying air. 105 The oil is thereby forced up through a pipe 12 which reaches nearly to the bottom of the tank, and which emerges from the top thereof and is provided with a valve 13 to regulate the oil-flow. From the valve, a pipe 14 conducts the oil to the retort or vaporizer, designated generally as 19, and

shown, for example, as employed in heating an ordinary house steam-boiler 16, although the invention is not limited to such use, nor is it always necessary to consume immediately the gas which is produced by the vaporization of the oil.

At the boiler the pipe 14 is coupled at 17 to the straight or tangent end 18 of a small-diameter pipe which forms a vaporizing retort in the form of a coil 19, preferably of two or more whorls. This retort-coil sets in the space that has been usually occupied by the fuel of the house-warming boiler. Said coil encircles a circular cresset or fire-box 15, which rests upon legs 20 standing within the usual ash-pit of the boiler (from which the usual fuel-grate has been removed). Said cresset or fire-box is shown, by way of illustration, as formed of a base 21 of fire-brick or other plastic molded refractory material resting upon a metal bed 22, to which the legs 20 are secured. The fire-box includes a cap 23 having flame-outlets 24 in its side walls, just below the encircling coil 19, whereby the coil is wrapped in and heated by flames escaping from the fire-box. The coil is made of metal of suitable stability. By this means the fuel-oil is vaporized which reaches the coil through the pipe 14. The flames also serve to heat the water 25 in the boiler 16, to form steam.

Preparatory to vaporizing the first of the oil, flames are produced in the fire-box temporarily by means of a supply of illuminating gas. The fire-box receives flames from a Bunsen burner, preferably a pipe whose mixing chamber is in the form of an elbow, that is, a horizontal chamber 26, leading to a vertical chamber 27, fitting into the open base 22 of the fire-box, the tip 23 opening into the overlying flame-chamber 28. The household gas for temporary use is led from a main 29, connected to the usual house supply, and having a flow-controlling valve 30; this main 29 having a jet 31 introduced into the air-intake end 32 of the Bunsen burner, so that the house gas mixes with air in the Bunsen burner 26, 27. This mixture is ignited at the discharge end or tip 33 of the Bunsen burner, the flames filling the cresset or fire-box and escaping through the outlets thereof and heating the retort-coil until it becomes red hot, or at least sufficiently hot to vaporize oil. As soon as the retort is heated, oil is admitted thereto by opening valve 13. From the retort the pipe is continued tangentially and curving broadly at 37 to deliver the gas to a needle-valve 34, having a handle 35 and a nozzle 36, which is also introduced in the air intake 32 of the Bunsen burner. The oil in the coil is vaporized by the heat. The needle-valve 34 is opened, and the vapor or gas into which the oil has been converted flows past the needle-valve and

discharges through the jet 36 and into the mixing chamber of the Bunsen burner, and at the tip 33 thereof it is ignited, producing a blue flame, economical of oil as compared with oil-spray burners. The blue flame from the oil-gas is now used for heating the retort, and at this time the supply of house gas may be shut off by means of the valve 30, which remains closed until after the oil in the tank 11 is used up.

The pressure of the air in tank 11 forces the oil out and into the retort as fast as the vapor is consumed by the burner; the rate of consumption and heat of the boiler being controlled by the needle-valve 34.

The speed of delivery of the oil-gas is very great, minimizing the formation and eliminating the deposit of lampblack or carbonous substance from the distillation. The diameter of the pipe forming the coil is made very thin or small to increase the speed, hence the retort is given the form of a circular race, giving the high speed of the gas which is important in overcoming the tendency to clotting of solid carbon. The bore of the coil and of the gas-delivering end 37 thereof is made very smooth, to reduce friction and conduce to speed of gas flow, and avoid catching lampblack or deposits. The bore of the coil may be as small as one-eighth or one-quarter of an inch in many cases, and larger in some cases. This reduction augments the speed of the gas, practically eliminating deposit of carbon, and also with the result that the oil body, since it exists in the form of a long, thin stream, is more accessible to the heat, and is more readily converted into gas, especially since the small-bore pipe can be coiled two, three or more times around the fire-box. The very thin and long body of oil is more readily heated, on account of its attenuation and length, than would be the case if the same oil were contained in a coil having a single whorl of say one-half an inch inside diameter.

The flame continues until the oil is used up, or until the valve 34 is closed to stop the operation of the boiler 16. The valve 34 affords such regulation that only a moderate amount of oil needs to be consumed in moderate weather, while more oil may be supplied to the boiler for cold weather.

The coil or retort may be supported in a set of hangers in the form of metal hooks 38, depending from metal straps 39 which cross the top of the cap and are joined by a rivet 40. Clips 41 may also be provided for holding the whorls of the coil together. The tile-cap 23 may consist of a top with a downwardly-extending circumferential flange fitting within a brim or annular seat 42 in the top of the base 21. The flame-outlets 24 may be placed at short intervals around the cap, to permit the spreading flames to lap

the coil at all points in its circumference. The device may be readily applied to existing furnaces, although the invention is not limited to the details shown.

5 The invention produces a useful dry or stable gas.

An air-pump, such, for instance, as a bicycle-pump 43, may be employed for securing the air pressure which feeds the oil to the furnace; this pump delivering compressed air through a valve 44 to an air-tank 45, which has a delivery valve 46, connected by a reducing valve 47 to an inlet valve 48 controlling the pressure in the oil-tank 11.

10 The air-tank 45 is charged with compressed air of say twenty pounds pressure, the pressure being reduced to say ten pounds in the oil-tank, whereby one charging of the tank 45 may be sufficient to expel all the oil in 15 the tank 11 at approximately uniform pressure.

The discharging end 37 of the retort-coil enters the jet body 49, which contains the needle-valve 34 at an acute angle to the 20 direction of the needle. The flow of the gas through the needle-valve is ample and unimpeded, while the valve-handle 35 is accessible, and the needle-valve is of simple construction. The tip of the gas-pipe 37 25 may be fitted into socket 50 integral with the jet body containing the needle-valve, and the angle formed between the pipe 37 and the needle-valve 34 may be much sharper than shown, so as to favor the speed of the gas, and to minimize the pocketing of the gas 30 within the needle-valve-case 49, and to insure that the gas has enough current or flow to clear out any particles of soot that may enter 49, even when the needle-valve is closed 35 to a slow-feed point. Said casing may be secured by means of a pair of brackets 51 upon the intake or mouth of the Bunsen burner, the mouth being, however, of sufficient diameter to permit free inflow of air 40 into the burner.

In operation, the supply of ordinary illuminating house-gas flows from the main 45 and escapes from its jet 31 into the mouth 32 of the Bunsen burner, where it is ignited by the use of a match, producing a flame at the discharge 33 of the Bunsen burner, the flame heating the retort. Such illuminating gas premixes with the air of the Bunsen burner. The gas-jet terminates just within 50 the mouth of the Bunsen burner. The house-gas produces a flame, which is emitted from the outlets 24 of the fire-box, and renders the retort-coil usually red hot. At this time there is no oil in the retort. As 55 soon as the retort becomes hot, valve 13 is opened, and oil is forced from the pressure-tank by the compressed air, and enters the retort under pressure, and circulates around the fire-box, while the blue flame of the 60 house-gas continues. The oil in the coil is

converted into gas, which passes through the outlet-pipe 37, and discharges through the needle-valve into the mouth of said Bunsen burner. The jet of oil-gas sucks the air into the Bunsen burner. The gas mixes with air 70 and thence discharges from the tip 33 of the Bunsen burner, making a powerful blue flame, which plays upon the retort-coil 19, thereby converting more oil into gas for producing more flame, so that the emission 75 of flame from the Bunsen burner is continued until all the oil in the tank is used up. The supply of illuminating gas, however, is turned off as soon as the oil-gas is first ignited, and thereafter the oil-gas burns 80 alone.

While the fire-box may be made of metal, still tile or other refractory molded material is preferred. The tiles are heated by the flames and emit slow, radiant heat, thereby heating the boiler and the Bunsen burner 85 economically as compared with direct heat of combustion, which is very rapid and tends to waste up the chimney of the boiler.

It will be seen that from the arrival of 90 fresh oil to the intake end of the retort, until the escape of said oil in the form of gas through the needle-valve, the progress is very rapid. The raceway is very direct and totally free from ripples or other obstructions which would collect lampblack. Upon the extremely long race of thin diameter 95 plays the blue flames from the fire-box, thus giving maximum heating effect and maximum speed, and minimum cooling of the 100 carbon into lampblack on the way to the needle-valve.

The pressure of the oil-gas is due largely to the vaporization of the oil in the retort or generator; there being, in fact, more pressure generated in the retort than is required. The needle-valve is adjustable to control the flow of the oil-gas and thereby control the heat of the burner and fire-box and coil, as well as the heat of the steam-boiler. A good 105 blue flame can be secured by regulating the needle-valve and using a proper size of Bunsen burner. The combustion depends upon the ratio of the air mixing with the oil-gas, and this ratio is regulated by varying the size, that is the length and diameter of the mixing chamber of the Bunsen burner. The tile fire-box becomes incandescent and so remains during the operation of the 110 burner.

This oil-gas is dry, which is ascribed to the employment of multiple coils giving great length with small diameter of pipe used in the retort, and it is heated to such a temperature (around 600 degrees) that it 115 is no longer moist.

The oil producer and burner are adapted for light or heavy furnace-oil, say of grades from 28 to 40 Baumé.

Variations may be resorted to within the 120

scope of the invention, and portions of the improvements may be used without others.

Having thus described my invention, I claim:

5. 1. The combination with an automatic fuel-oil supply, of a retort in the form of a long coiled tube having a small, smooth bore, a Bunsen burner at the delivery end of the retort, and means for heating the retort by 70
burning the mixed air and gas from the Bunsen burner, said heating means including a cresset surrounded by said coils and heating the same, said Bunsen burner opening into said cresset. 75
15. 2. The combination of an oil-tank, a retort, an automatic and regulatable apparatus for forcing oil from said tank to said retort, said retort in the form of a long coiled tube having a small, smooth bore, a 80
Bunsen burner at the delivery end of the retort, means for heating the retort by burning the mixed air and gas from the Bunsen burner, and an adjustable heat-controlling valve, said heating means including a cresset 85
surrounded by said coils and heating the same, said Bunsen burner opening into said cresset. 90
30. 3. The combination with an automatic fuel-oil supply, of a retort in the form of a long coiled tube having a small, smooth bore, a Bunsen burner at the delivery end of the retort, and means for heating the retort by burning the mixed air and gas from the Bunsen burner, said heating means including 95
a cresset into which said Bunsen burner discharges, said cresset having lateral flame-outlets and said coil mounted in position to be heated by the flames from said outlets. 100
40. 4. The combination with an automatic fuel-oil supply, of a retort in the form of a long coiled tube having a small, smooth bore, a Bunsen burner at the delivery end of the retort, means for heating the retort by burning the mixed air and gas from the Bunsen burner, and a fire-box into which said Bunsen burner discharges, said fire-box having 105
flame-outlets adjacent to said coil for heating the same and said coil surrounding said fire-box above said outlets, means being provided upon said fire-box for suspending the coil which surrounds the box, and means for clipping the whorls of the coil together, with each whorl spaced from the others to afford the flames access thereto. 110
50. 5. The combination with an automatic fuel-oil supply, of a retort in the form of a long coiled tube having a small, smooth bore, a Bunsen burner at the delivery end of the retort, means for heating the retort by burning the mixed air and gas from the Bunsen burner, and a fire-box into which said Bunsen burner discharges, said fire-box having 115
flame-outlets and said coil surrounding said fire-box above said outlets, said fire-box being formed of refractory plastic material including a base into which said Bunsen burner discharges, and also including a cover having the flame-outlets. 120
60. 6. The combination with an automatic fuel-oil supply, of a retort in the form of a long coiled tube having a small, smooth 125
bore, a Bunsen burner at the delivery end of the retort, means for heating the retort by burning the mixed air and gas from the Bunsen burner, and a fire-box into which said Bunsen burner discharges, said fire-box having flame-outlets and said coil surrounding said fire-box above said outlets, said fire-box being formed of refractory plastic material including a base into which said Bunsen burner discharges, and also including a cover having the flame-outlets. 130

- through, and coiled repeatedly about said cresset above said vents, to expose a long thin stream of fluid to the heat from the flames and the cresset, said vaporizing pipe opening into said Bunsen burner pipe, the length of the coil being sufficient and the vaporizing pipe being sufficiently thin to enable the oil to be converted into substantially dry gas for discharge into said Bunsen burner pipe.
- 10 11. Apparatus as set forth in claim 10, provided with means adjustable for regulating the heat of the cresset.
12. Apparatus as set forth in claim 10, provided with a priming supply of gas also
- 13 opening into said Bunsen burner pipe, and provided with means for turning on and off the priming gas.
14. Apparatus as set forth in claim 10, in which the oil-vaporizing pipe is formed in
- 20 a single piece, with smooth, uninterrupted bore from end to end, and includes a reach extending from said coil to the intake end of said Bunsen burner, said reach merging tangentially into the delivery end of said coil, said coil and reach being pocketless, cornerless and not sufficiently bent to form a lodgment for accumulation of solid carbonous deposits therein from vaporization.
15. Apparatus as set forth in claim 10, in which the coil is of such length and sufficient thinness to lack rigidity, and rests upon which the different whorls of said coil are individually supported.

AXEL W. HALLENBORG.
